UNITED STATES PATENT OFFICE.

SAMUEL R. BAILEY, OF AMESBURY, MASSACHUSETTS.

SLEIGH.

SPECIFICATION forming part of Letters Patent No. 379,303, dated March 13, 1888.

Application filed October 15, 1887. Serial No. 252,426. (No model.)

To all whom it may concern:

Be it known that I, SAMUEL R. BAILEY, of Amesbury, in the county of Essex and State of Massachusetts, have invented a new and 5 useful Improvement in Sleighs, which improvement will, in connection with the accompanying drawings, be hereinafter fully described, and specifically defined in the appended claims.

Figure 1 is a side elevation of a sleigh embodying my invention. Fig. 2 is an enlarged detached horizontal section taken as on line Z Z, Fig. 1. Fig. 3 is an enlarged detached vertical section taken as on line X X, Fig. 2.

My invention relates to that class or kind of 15 sleighs which have a recessed or set-back dasher; and it consists in features of novelty hereinafter fully described, and pointed out in the claims.

Referring again to the drawings, A represents the "sleigh-top," as it is termed by the 20 trade; B, the runner; C C, the standards; D D, the bars on which top A rests; E, the metal braces, and F the shaft-hangers, all said parts, except bars D, being duplicated upon the 25 respective sides of the sleigh.

H represents the curved side bars of the dasher, which extend downward to the bottom of top A and serve as the front corner-pieces thereof. The dasher I, which extends 30 upward from top A the extent of bars H, is secured in a rabbet therein, as is clearly shown in Figs. 2 and 3, said dasher extending from side to side of the sleigh in the usual manner.

A re-enforcing iron, b, plano-convex in cross- 35 section, is secured to each bar H in the usual manner, as shown in Figs. 2 and 3, and the shoes a of runners B extend up the length of said runners. For the purpose of connecting the upper end of the runners B with the 40 dasher at its side bars, H, in a neat, strong, and inexpensive manner, and so that it may for any purpose be quickly disconnected therefrom, I have invented the metallic coupling G, which consists, essentially, of the back plate, 45 h, the side cheeks, d, the hollow neck c, hav-

ing a concave seat to receive iron b, and with a scroll-like head, e, formed hollow, as shown by cavity f, Fig. 3. The lower end of back plate, h, of said coupling is secured to runner B by a rivet, i, which passes through and secures together the runner, the coupling, and shoe a, while bolt g unites the runner, the shoe, the dasher, the coupling, and iron b, as shown in Figs. 2 and 3. Said coupling is formed of malleable iron or other suitable cast 50 metal, and is preferably of an ornamental or carved-work pattern, as shown. It receives into cavity f the extremities of runner B and shoe a, and serves as a means, with bolt g, to unite the runner and dasher in a very im- 55 proved manner.

The style and plan of the sleigh, the number of standards and bars, and the brace-work E may all be varied as desired without departing from the substance of my invention, as 60 they constitute no part thereof, it consisting in a metallic coupling formed to receive in a suitable cavity therein the upper portion of the runner and its shoe and having a seat to receive the re-enforce iron of the dasher, together with a passage for the securing-bolt by which the parts are held together, as also the combination of said coupling with the coacting parts; hence 65

I claim as my invention—

1. The metallic coupling G, formed to receive the upper ends of the runner and its metallic shoe, and with a seat or suitable bearing for the re-enforce iron of the dasher, and with suitable passages for bolts or rivets 80 whereby the respective parts are firmly secured together, all substantially as specified.

2. The combination of coupling G, formed substantially as described, runner B, its iron a, dasher I, its bars H, and re-enforce iron b, 85 and the securing-bolt g, all as specified.

SAMUEL R. BAILEY.
